CLAIM

The ornamental design for a watercraft mounting clip, as shown and described.

DESCRIPTION

FIG. 1 is a left front perspective view of a watercraft mounting clip showing our new design;

FIG. 2 is a right rear perspective view thereof;

FIG. 3 is a front elevation view thereof;

FIG. 4 is a rear elevation view thereof;

FIG. 5 is a top plan view thereof;

FIG. 6 is a bottom plan view thereof; and,

FIG. 7 is a side elevation view, the opposite side being a mirror image thereof.

The views of the watercraft mounting clip not shown form no part of the claimed design. The broken lines depicting a hole represent environmental elements only, and form no part of the claimed design.
